UNITED STATES PATENT OFFICE.

WILLIAM D. ASH, OF KIRBYVILLE, TEXAS, ASSIGNOR OF ONE-HALF TO JAMES A. HERNDON, OF KIRBYVILLE, TEXAS.

KEYING DEVICE FOR CUTTER-HEADS.

1,046,937.

Specification of Letters Patent. Patented Dec. 10, 1912.

Application filed May 26, 1911. Serial No. 629,746.

To all whom it may concern:

Be it known that I, WILLIAM D. ASH, a citizen of the United States, residing at Kirbyville, in the county of Jasper and State of Texas, have invented new and useful Improvements in Keying Devices for Cutter-Heads, of which the following is a specification.

This invention relates to means for attaching tools to shafts, such as cutter heads, profile attachments, pulleys, wheels and the like.

The object of the invention is to provide an improved construction for conveniently and expeditiously attaching cutter heads and like devices to rotating shafts and for adjusting the position of the cutter head, pulley or like device upon the shaft.

The invention consists in providing a cutter, pulley or the like with a centrally tapered hole in which is mounted a clamping sleeve having a threaded outer end to receive an operating nut. Provision is made for keeping the nut in constant engagement with the cutter head, pulley or the like, while the clamping sleeve is in position and for conveniently removing the nut when desired, this means consisting in a split collar having nut and cutter head engaging flanges. The particular advantage in this type of device resides in the fact that if the sleeve becomes loose in the head or pulley the nut cannot become disengaged from the sleeve in rotation of the parts, it being always held in the same relation with the cutter head or hub of the pulley irrespective of the position of the sleeve therein.

Further objects of the invention will appear as the following specific description is read in connection with the accompanying drawings, which forms a part of this application, and in which:

Figure 1 is a side elevation. Fig. 2 is a longitudinal section therethrough. Fig. 3 is a detail side elevation of the clamping sleeve. Fig. 4 is a detail top plan view of the connecting collar shown on an enlarged scale. Fig. 5 is a transverse section taken on the line 5—5 of Fig. 1. Fig. 6 is a similar view taken on the line 6—6 of Fig. 1.

Referring more particularly to the drawings, 1 represents a cutter head which is provided with a central longitudinal bore 2 gradually increasing in size from one end 55 to the other and having communicating

therewith the longitudinal channels 3 which extend from the large end of the bore inwardly and have their inner walls parallel with the walls of the bore. Mounted in the bore is a hollow sleeve 4 which is provided with longitudinal slots 5 and constructed of a material which will have sufficient resiliency, when the sleeve is drawn into the bore, to contract and bind upon the shaft 6. The outer end of the sleeve is provided with a closing end 7 and threaded in this end is an adjusting screw 8 having a wrench receiving head 9 and a binding or jam nut 10 mounted thereon. The walls of the sleeve 4 are provided with apertures 11 having inwardly tapered walls and seated in the apertures are plugs 12 which travel in the channels 3, so as to prevent the sleeve from turning relatively to the cutter head, pulley or like device in which the sleeve is mounted.

Adjacent the upper end of the cutter head there is formed an internal annular channel 13 which communicates with the bore and is adapted to receive the sectional retaining ring or collar 14. This retaining ring is constructed of a plurality of sections 15, 16, 17 and 18, the sections 16 and 17 being provided with beveled ends so as to permit the insertion of the section 18 which is provided with correspondingly beveled ends.

Mounted upon the outer threaded end 19 of the sleeve 4 is an operating nut 20 having a plurality of sockets 21 arranged around its periphery to receive a spanner wrench or the like. Communicating with the bore through the nut is an annular channel 22 which is adapted to receive the upper flange of the sectional collar 14, the lower flange being received by the channel 13.

In the application of the device to a cutter head having a channel 13, the nut is placed upon the cutter head and the sections 15, 16 and 17 placed in position with their upper and lower flanges in the channels 22 and 13 respectively. These sections are then spread apart so as to permit the insertion of the section 18. The sleeve 4 is then inserted in the bore of the cutter head and the nut 20 partially turned thereon. The device is then placed upon the end of the shaft 6 and the screw 8 adjusted so as to properly position the cutter head. The nut 20 is then further turned until the sleeve clamps the shaft in position. It will be observed that this type of connection may be

utilized for securing profile attachments of planers, pulleys, automobile wheels to their axles, and in fact connect any type of device to an axle which is adapted to rotate therewith. The closing end 7 and the adjusting screw 8 may be dispensed with and the shaft passed directly through the sleeve if found to be necessary.

Having thus described the invention, what I claim as new is:—

The combination with a shaft and a device to be connected thereto having a tapered bore, of a split shaft-receiving sleeve mounted within the bore and having

tapered walls and a threaded end, said device having an annular channel communicating with the bore, a nut threaded on the sleeve and having an annular channel, and a sectional retaining collar removably engaged with the annular channels of the device and nut and held in position by the sleeve.

In testimony whereof I affix my signature in presence of two witnesses.

WILLIAM D. ASH.
